UNITED STATES PATENT OFFICE.

ELMER A. SPERRY, OF BROOKLYN, NEW YORK, ASSIGNOR TO THE SPERRY GYROSCOPE COMPANY, OF BROOKLYN, NEW YORK, A CORPORATION OF NEW YORK.

GYROSCOPIC PENDULUM.

Application filed March 17, 1928. Serial No. 625,831.

This invention relates to gyroscopes and more particularly to gyroscopic pendulums adapted to be mounted on movable craft such as aircraft. Such gyroscopes may be variously employed, as for controlling a level indicator, banking indicator, base-line for automatic pilots, stabilizers, etc.

It is an object of this invention to provide an improved means for damping or suppressing the oscillations of said pendulum, so that a correcting torque is immediately applied which is proportional to the disturbing force tending to cause a tilt.

A further object is the provision of damping means capable of being actuated by air, and of novel means for supplying the necessary air and suitably controlling the same.

A further object is the provision of means whereby the travel of the craft through the air furnishes the air supply for operating said damping mechanism and also preferably the gyro-rotor as well.

A further object is the provision of an air supply for said rotor and said damping mechanism which will deliver air under pressure.

Other objects and advantages of this invention will be in part obvious and in part specifically referred to in the specification.

30 In the accompanying drawings,

Fig. 1 is a front elevation of a device for utilizing the movement of a craft through the air to supply air under pressure.

Fig. 2 is a vertical section of the device shown in Fig. 1.

Fig. 3 is a detail showing the gearing for operating an air pump in the Fig. 1 device.

Fig. 4 is a vertical section through said pump.

40 Fig. 5 is a vertical section through a gyroscope embodying certain features of my invention.

Fig. 6 is a plan, with certain parts removed, of the gyroscope shown in Fig. 5.

45 Fig. 7 is a vertical section through a portion of a modified form of gyroscope.

Fig. 8 is a vertical section through a portion of a third form of gyroscope.

50 Fig. 9 is a plan view of a fan employed in the Fig. 8 device to supply air to the damping device.

Fig. 10 is a plan view of the damping device.

Referring to Figs. 1 to 4 of the drawings, there is shown a device for utilizing the movement of a craft through the air to create a supply of air under pressure. The device comprises a casing 10 having preferably a stream-line contour and adapted to be applied to the moving craft. When applied to the aircraft, it is mounted upon one of the exposed struts of the machine. The casing comprises a rear conduit section 11, a pump section 12, and a rotatable driving or propeller section 13. Within the pump section 12 is mounted a pump 14 (see Fig. 4) which may be of the blower type having interlocking blades or gears 15, 16 within a casing 20 and provided with an inlet 17 on the forward side and an outlet 18 on the rearward side. The gears are fixed upon shafts 21 and 22 adapted to be driven from the driving section 13. Said section is provided internally with spokes 25 fixed to a hub 26 mounted upon a shaft 27 fixed to the pump casing 14 and having a head 28 to hold said hub thereon against outward movement. To the exterior of casing 13 are fixed propeller blades 29 adapted to be rotated by the wind to rotate section 13 and hub 26.

The gears 21 and 22 are driven from the section 13 by a suitable gearing which may comprise a pinion 31 movable integrally with a hub 26 and meshing with a gear 32 on a stub-shaft 34 carried by the pump casing. Also carried by shaft 34 is a gear 33 which meshes with a gear 35 fixed to the outer end of shaft 21 and meshing with a similar gear 36 fixed to the outer end of shaft 22. The gears 15 and 16 of the pump are thus driven by the rotatable section 13. To balance the gear drive, a gear 37 may be provided at the opposite end of shaft 21 outside of the pump casing at the rear thereof, meshing with a gear 38 on the opposite end of shaft 22.

Passage of the craft through the air thus results in operation of the pump. The air is supplied to the inlet 17 of said pump through an opening 45 in the nose of section 13 in the direction of travel of the craft. The air is driven by the pump through outlet 18 under pressure into compartment 11 to the rear thereof and thence into a conduit 47 which conducts the air to the mecha-

nism which utilizes it. The section 11 may be provided with a plurality of baffle plates 48 to prevent passage of oil and other foreign matter to the conduit 47.

In the present instance the air supplied by the device 10 is utilized for driving a gyroscope. Said gyroscope may comprise a casing 50 in which is mounted a rotor 51 fixed to a spindle 52 supported in suitable bearings 53 and 54. The lower bearing is supported on a bracket or partition 55 dividing the casing into upper and lower sections, said partition having openings 56 therethrough, permitting ready communication between the sections. Said partition is provided in its upper surface surrounding bearing 54 with a reservoir 57 for lubricant, such as oil, which is fed upwardly by a wick through a tube 58, thence into a trough 59 and into the space between the bearing and the shaft 52.

The gyroscope is pivotally mounted by trunnions 61 in a gimbal ring 60 which is in turn pivotally mounted by trunnions 62, at right angles to trunnions 61, in standards 63. The rotor 51 is provided with a plurality of buckets 65 in its periphery. For driving the rotor the air pumped from the device 10 may be utilized. For this purpose the conduit 47 is connected to the standards 63 adjacent the trunnions 62. Said standards and trunnions are provided with bores 66 and 67 which communicate with conduit 47 so that the air delivered by the pump passes into the interior of the gimbal ring 60 which is hollow. The interior of said ring is in communication with a bore 68 extending into trunnions 61 and from said bore into circular, vertically-positioned reservoirs 69 which at points opposite the buckets are provided with nozzles 70 directed against said buckets.

After imparting its momentum to the rotor, the air spills off the buckets into the lower section of the casing 50 by way of slits 71 cut in the lower part of the rotor, where its discharge may be employed to actuate a mechanism for damping or preventing the oscillations of the gyroscope. For this purpose, there are symmetrically disposed adjacent the lower sides of the casing a plurality of rows of exhaust ports or nozzles 72. In the drawings each row is shown as comprising nine ports, each turned substantially tangential to the casing, and tapered at its outer end to increase the velocity of air passing out of the casing. A pendulum 75 is suspended from the bracket or partition 55 by means of a universal suspension comprising a member 73 in which said pendulum is pivoted on a substantially horizontal axis, said member 73 being in turn pivoted on a horizontal axis at right angles to said first axis in a member 74 fixed to the under side of the bracket. Said pen-

dulum has its lower surface in the form of an arc 76 closely adjacent the inner surface of the lower, bowl-like section of the casing. In its normal position it closes substantially half of the ports of each set, in this case, 70 four and a half. Normally, therefore, the air which spills off the buckets passes out through half of the total number of ports 72. This number may, of course, be varied to suit particular cases.

In the normal position of the apparatus, both the casing or gyroscopic pendulum 50 and the pendulum 75 are vertical with their vertical axes in alignment. The same number of ports 72 in each set is exposed and the air issues from each set at the same rate and in the same quantity. The damping pendulum 75 being a simple pendulum suspended below the axis of suspension of the casing, has a very much shorter period than the gyroscope and will be quickly displaced from the vertical position by the action of acceleration forces. Any movement of the short-period pendulum relative to the casing, however, will uncover more ports of certain of said sets (those furthest from the vertical) than of the others, so that a greater quantity of air discharges through said first sets and causes reaction on the casing in a direction which tends to prevent displacement of the casing from the vertical. By providing a relatively large number of ports in each set positioned close together, the following important result is obtained, i. e., the number of ports uncovered (and hence the restoring force) will be proportional to the disturbing or unbalancing force. Thus, a slight displacement of the short period pendulum, such as due to a small acceleration force, may result in uncovering only one or two ports of a particular set or sets, with a correspondingly slight restoring force on the gyroscope. A large displacement of the short period pendulum due to a larger acceleration force will however, uncover five, six or even nine ports, as the case may be, with a corresponding increase in the restoring force being developed by the air passing through the ports. The direction of rotation of the gyroscope is so arranged with respect to the air jets, that the torque exerted by the jets tends to reduce the tilt or deviation from the vertical of the gyroscope due to acceleration forces.

This damping means may be employed in cases where the rotor is spun by other means than air, as, for instance, by a motor, the air being supplied through an opening in the casing and forced downwardly by a fan rotated by the motor. For a detailed description of such construction, reference should be had to the patent of Mortimer F. Bates, No. 1,518,892 dated December 9, 1924.

Theoretically the torque exerted by the uppermost jets 72 would be somewhat less

than the torque exerted by the lowermost jets, owing to the fact that the latter act through a longer lever arm about the horizontal axis of support of the gyroscope than the former. In order to equalize this torque as much as possible without causing the parts to strike the gimbals, I prefer to position the jets 72 so that the axis from which they are struck coincides with the cardinal center O of the gyroscopic pendulum instead of coinciding with the pivot of pendulum 75 as does the curvature of the interior of the bowl. Preferably, also, the little pipes constituting the jets emerge from the bowl in radial lines struck from the said cardinal center O of the gyroscope as shown by the radial dotted lines R.

In a modified construction, the damping means of Fig. 5 may be supplied directly with air from the device 10 through the gimbal ring in addition to the air which spills from the buckets, instead of relying solely upon the latter supply. A somewhat greater pressure can be built up by this method within the bowl of the casing in which the damping pendulum 75 operates. For this purpose the gyroscope may be modified as shown in Fig. 7 wherein the circular, vertically-disposed reservoir 69 is provided not only with a nozzle adjacent the buckets of the rotor, but also with a second nozzle or orifice 80 near its lowermost point formed to direct a portion of the air in said reservoir downwardly into the bowl. A partition 81 separates the bowl from the upper portion of the casing in which the rotor operates, the rotor-driving nozzle being positioned above the partition and the damping mechanism and supply nozzle being positioned below the partition. One or more openings 82 may be provided in the casing above partition 81 through which the air discharges after leaving the buckets.

A modification which can be constructed from the Fig. 5 device is illustrated in Fig. 8. In this form, the rotor is again driven by air supplied from device 10 through the nozzle 70, the air discharging through openings 82. For operating the damper, however, a supply of air is drawn from the outside of the casing. For this purpose, there may be provided in the space between the bracket or partition 56 and the bottom of the rotor, an opening 85 to the exterior of the casing and one or more conduits or openings 86 extending through the partition 56 so that air may pass into opening 85 and then through conduit 86 to the bowl. For drawing air in through inlet 85 and sending it through conduit 86 at an increased speed, there may be provided a suction fan 90 fixed to the bottom of the rotor, so as to be rotatable therewith. Said fan comprises an upper annular plate 91 and a lower similar annular plate 92, each having a circular

indentation in its surface so that a vertical cross section through each plate will be substantially V-shaped with the apices of the V's toward each other and the inner arms of the V's longer than the outer arms. In this manner, there is formed an annular contracted portion 93, thus forming in effect an annular Venturi tube. The outer periphery of the tube rides closely adjacent the mouth 94 of the conduit 86, and this relative positioning will always be maintained since the Venturi tube is circular. In this manner any air entering conduit 86 must first pass through the fan.

To cause the fan to suck air continuously from the outside through inlet 85 and force it into conduit 86, the venturi is supplied with a plurality of symmetrically-disposed partitions 96 extending from the inner opening of the venturi toward the contracted portion (Fig. 9) and so inclined that with a given direction of rotation of the fan the partitions 96 will sweep air toward the contracted portion and thence through said portion at increased speed to the conduit 86. Rotation of the fan in the opposite direction will of course necessitate inclining of the partitions in the opposite direction.

The operation of the Fig. 8 device is as follows: Air from the device 10 drives the rotor as hereinbefore described. The rotor carries therewith the annular Venturi fan which sucks air from the outside through inlet 85 and forces it through the constricted portion of the venturi, thus greatly increasing the speed with which the air is delivered to conduit (or conduits) 86, and thence into the bowl to actuate the damping mechanism.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having herein described my invention what I claim and desire to secure by Letters Patent is:

1. In combination with a gyroscopic pendulum, of damping means therefor, comprising a casing on the gyroscope, means for creating a differential air pressure therewithin, an auxiliary pendulous device supported on said gyroscope, a plurality of groups of ports in said casing positioned so as to be partially covered by said pendulous device, each group comprising a plurality of

ports placed successively further from the normal position of said pendulous device whereby the number of ports uncovered by said pendulous device is proportional to the 5 forces tending to produce oscillation of the gyroscopic pendulum.

2. In combination with a gyroscopic pendulum, of damping means therefor, comprising a casing on said gyroscopic pendulum; said casing having a plurality of groups or ports, each group comprising a plurality of separate ports placed successively higher up on said casing, means for supplying air to said ports, and pendulous 15 means for covering and uncovering said ports.

3. In combination, a gyroscopic pendulum and means for damping the oscillations thereof, said means comprising a casing for 20 said pendulum, said casing having a plurality of laterally spaced groups of ports, each group having a plurality of vertically spaced ports, means for supplying air to said ports, a pendulum universally suspended in 25 said casing and having means for covering and uncovering said ports, so that relative displacement of said pendulums uncovers in certain of said groups a number of ports proportional to the degree of oscillation.

30 4. In combination, a gyroscopic pendulum and means for damping the oscillations thereof, said means comprising a casing for said pendulum, said casing having more than two symmetrically arranged sets of ports, 35 the ports of said sets being arranged at an angle to the horizontal, means for supplying air to said ports, a pendulum universally suspended in said casing and having means for covering and uncovering said ports, so 40 that relative displacement of said pendulums uncovers in certain of said sets a number of ports proportional to the degree of oscillation.

45 5. In combination, a gyroscopic pendulum and means for damping the oscillations thereof, said means comprising a casing for said pendulum, said casing having more than two sets of ports, said sets being symmetrically disposed and arranged at an angle to 50 the horizontal, means for supplying air to said ports, a pendulum universally suspended in said casing and having means for covering and uncovering said ports, so that relative displacement of said pendulums 55 uncovers in certain of said sets a number of ports proportional to the degree of oscillation.

6. In combination, a gyroscopic pendulum and means for damping the oscillations 60 thereof, said means comprising a casing for said pendulum, said casing having a plurality of sets of ports, said sets being symmetrically disposed and each set comprising a plurality of ports arranged in substantially 65 vertical planes, means for supplying

air to said ports, a pendulum universally-suspended in said casing and having means for covering and uncovering said ports, so that oscillation of said second pendulum uncovers in certain of said sets a number of 70 ports proportional to the degree of oscillation.

7. In combination, a gyroscopic pendulum and means for damping the oscillations thereof, said means comprising a casing for 75 said pendulum, said casing having a plurality of sets of ports, said sets being symmetrically disposed and each set comprising a plurality of ports arranged in substantially vertical planes, means for supplying air to said ports, a pendulum universally-suspended in said casing and having means for normally covering certain of the ports of each set and uncovering the remaining ports of each set, the number of ports normally uncovered being the same in each set, so that oscillation of said second pendulum uncovers in certain of said sets a number of 80 said normally covered ports proportional to the degree of oscillation and covers an equal 85 number of normally uncovered ports in the other sets.

90 8. In combination, a gyroscopic pendulum and means for damping the oscillations thereof, said means comprising a casing having a hemispherical lower section, said section having a plurality of sets of ports, said sets being symmetrically disposed and arranged at an angle to the horizontal, means for supplying air to said ports, a pendulum universally suspended at the center of said section and having means for covering and uncovering said ports, so 95 that oscillation of said second pendulum causes a number of ports proportional to the degree of oscillation to be uncovered in certain of said sets.

100 9. In combination, a pivotally-mounted gyroscope comprising a rotor adapted to be driven by air, an air-operated damping mechanism for said gyroscope and a single source of air supply for operating said rotor and said mechanism in series.

105 10. In combination, a gyroscope pivotally mounted upon a movable craft and comprising a rotor adapted to be driven by air, an air-operated damping mechanism for said gyroscope, and means whereby the movement of said craft furnishes the air supply for operating said rotor and said mechanism.

11. In combination, a pivotally-mounted gyroscope comprising a rotor adapted to be driven by air, an air-operated damping mechanism for said gyroscope, and a source of air supply for driving said rotor, said mechanism being operated by the air discharged from said rotor.

12. In combination, a pivotally-mounted gyroscope comprising a rotor adapted to be 120

- driven by air, an air-operated damping mechanism for said gyroscope, a source of air supply for driving said rotor and means whereby said mechanism is operated by the 5 air discharged from said rotor.
13. In combination, a pivotally-mounted gyroscope having a casing and comprising a rotor adapted to be driven by air, an air-operated damping mechanism for said gyroscope, said casing having a plurality of openings forming part of said mechanism, a source of air supply for driving said rotor, said air passing through said openings to operate said mechanism after dis- 10 charging from said rotor.
14. In combination, a gyroscope pivotally mounted upon a movable craft and comprising a rotor adapted to be driven by air, an air-operated damping mechanism for 15 said gyroscope, means whereby the movement of said craft furnishes the air supply for driving said rotor, and means whereby said mechanism is operated by the air discharged from said rotor.
15. In combination, a support, a hollow gimbal ring pivotally mounted in said support, a gyroscope comprising a rotor, a casing for said rotor pivotally mounted in said ring, an air-operated damping mechanism for 20 said gyroscope, means for supplying air to said rotor through said ring, and means whereby said mechanism is operated by the air discharged from said rotor.
16. In combination, a gyroscope pivotally mounted upon a movable craft and comprising a rotor adapted to be driven by air, an air-operated damping mechanism for said gyroscope, a source of air supply, means for directing the air to drive said rotor, and means for directing the same air 25 to operate said mechanism.
17. In combination, a gyroscopic pendulum and means for damping the oscillations thereof, said means comprising a casing for said pendulum, said casing having a plurality of ports, means for supplying air to said ports, means for covering and uncovering said ports, and means whereby the number of ports uncovered by said last-named means is proportional to the degree 30 of oscillation of said pendulum, said ports having their axes substantially coincident with the cardinal center of the gyroscopic pendulum.
18. In combination with a gyroscopically controlled pendulum, a simple universally mounted pendulum, means brought into action by relative movement of the two pendulums in any direction for bringing into action a force counter-acting said movement, said means including means for varying the amount of force brought into action in accordance with the relative degree of tilt 35 through wide angles.
- In testimony whereof I have affixed my 40 signature.

ELMER A. SPERRY.
